WINDOW FASTENER

Harry J. Jackson, Arlington County, Va.

Application April 22, 1936, Serial No. 75,835

14 Claims. (Cl. 292—337)

This invention relates to an improvement in window fasteners of the type employed for fastening the upper and lower sash together, in which a fastening device extends transversely through one of the sash and into the adjacent edge of the other sash.

Heretofore, a difficulty has been encountered in matching the holes of the adjacent edges of the sash to receive a fastening member therefor, and the holes are sometimes formed too large or not true in size and location, with the result that the fastening member would not snugly fit the holes in the sash.

The object of my invention is to provide an expandable fastening device capable of being expanded to fit the holes formed in the adjacent edges of the sash and thereby obtain a proper fit, avoiding unnecessary rattling and jamming of the parts.

This object is accomplished in the preferred embodiment of the invention by the provision of expandable members backed up by yieldable bushings, and by the provision of an expandible securing bolt capable of fitting in the tubular members when the latter are expanded into place in the adjacent edges of the sash.

I have illustrated a preferred embodiment of the invention in the accompanying drawing, in which:

Fig. 1 is a vertical sectional view of the adjacent edges of the window sash, showing the invention applied thereto, partly in elevation;

Fig. 2 is a face view thereof;

Fig. 3 is a view similar to Fig. 1, but enlarged and having parts of the fastening in section;

Fig. 4 is a transverse sectional view on the line 4—4, of Fig. 3;

Fig. 5 is a side elevation of the fastening bolt removed;

Fig. 6 is a side elevation of the guide sleeve;

Fig. 7 is an end elevation thereof;

Fig. 8 is a vertical sectional view of the corrugated socket; and

Fig. 9 is an end elevation thereof.

The invention is shown as applied to the adjacent edges of upper and lower window sash designated by the numerals 1 and 2, respectively, and which have holes or openings 3 and 4, formed therein to receive the window fastening. If these holes are not formed of exactly the right size to fit the fastening member inserted therein, or if they are not in proper alignment when the sash are closed, the fastening device will not fit snugly with the result of rattling and insecure fastening of the window.

In order to avoid this objection, I have provided an expandible socket 5 in the sash 1, which socket is made in two parts, as shown in Figs. 8 and 9, so as to be expanded to fit the hole snugly. To permit of such expandible action, a bushing 6 of yieldable material, such as soft rubber, is placed in the hole 3, within which the split socket 5 is disposed. The socket 5 is provided with flanges 7 on its inner end to be secured by screws 8 to the sash 1.

The opening 4 in the sash 2 has a split sleeve 9 extending therethrough. This sleeve 9 is likewise in two parts, as shown in Figs. 6 and 7, so as to be expanded to snugly fit the hole 4, but between the sleeve 9 and the surface of the hole 4 is a yieldable bushing 10, such as rubber, which permits the expansion of the sleeve 9 to fit the hole. The inner end of the sleeve 9 has flanges 11 thereon, to receive fastening screws 12 for securing the parts of the guide sleeve 9 to the sash 2.

A fastening bolt 13 is adapted to extend through the sleeve 9 and into the socket 5 for securing the sash together. This fastening bolt 13 is likewise expandible, being formed as a rolled tube, 25 split at one side, and having a handle 14 at one end thereof, capable of being grasped for removal of the fastening bolt.

The socket 5, sleeve 9, and bolt 13, preferably are formed of sheet metal, rolled and spun into proper shape, in the course of which shaping, the socket 5 is provided with female corrugations 15 in the interior thereof, while the inner end of the fastening bolt 13 is similarly corrugated at 16 for interfitting with the corrugations 15 in the socket to form a tight connection therebetween, to hold the fastening bolt in place and to securely fasten the window sash.

In assembling this fastening device, the holes 3 and 4 are bored in the sash, after which the rubber bushing 6 is inserted into the hole 3 and the socket 5 inserted in the bushing 6 and expanded to tightly fit the hole, after which the screws 8 are inserted to fasten the sections of the socket 5 in place.

In a similar manner, the rubber bushing 10 is inserted into the hole 4 and the sections of the guide sleeve 9 are introduced therein and expanded to fit this hole tightly, after which the screws 12 are inserted to hold the sections of the sleeve 9 in place. Then the fastening bolt 13 is passed through the sleeve 9 and into the socket 5, and is expanded as much as necessary to conform permanently to the expanded size of the sleeve 9 and socket 5 and has its male corruga- 55

tions 16 turned into the female corrugations 15, in the socket 5 for secure fastening of the parts together, snugly and tightly, preventing rattling or jamming of the parts of the fastening or window.

If desired, a cover plate 17 may be secured over the end of the fastening, as shown in Figs. 1, 2, and 3, to enclose the same, being provided with only a hole therethrough for passage of the bolt 13.

I claim:

1. In a window fastening, expansible guide elements adapted to be located in separate openings, and a fastening bolt extending into said guide elements and expansible approximately throughout its length to fit the respective expansible guide elements when expanded.

2. In a window fastening, expansible guides adapted to be located in openings, resilient bushings surrounding the guides in the openings, and an expansible fastening bolt extending in said guides for securing the adjacent portions of the sash together.

3. In a window fastening, an expansible socket, an expansible guide sleeve, yieldable bushings surrounding said socket and sleeve, and an expansible bolt extending through the sleeve and into the socket for fastening window sash together.

4. In a window fastening, bushings of yieldable material adapted to be inserted in separate openings of window sash, a split socket inserted in one of said openings and expanded to fit the yieldable material, means for holding said socket in expanded condition in the opening, a split sleeve inserted in the other bushing and expanded to fit the same, means for securing said sleeve in expanded relation, and an expansible fastening bolt extending through the sleeve and into the socket for securing the window sash together.

5. In a window fastening, yieldable bushings adapted to be inserted in openings of window sash, a socket in one of the openings and expanded to fit the bushing snugly, means for securing the socket to the sash in expanded position, an expansible sleeve in the other opening, means for securing said sleeve to the other sash in expanded condition snugly fitting the bushing and an expansible fastening bolt extending through the sleeve and into the socket and expanded to fit the same, said bolt and socket having interfitting corrugated portions for securing the bolt in place therein.

6. In a window fastening, expansible guide members adapted to be inserted in upper and lower window sash, and an expansible fasten-

ing bolt adapted to extend in said fastening members, said guide members and bolt being expansible throughout their lengths to fit each other and openings in the sash.

7. In a window fastening, an expansible socket, an expansible guide sleeve, and an expansible fastening bolt, all formed of sheet metal and split for expansion to fit openings in window sash. 5

8. In a window fastening, an expansible socket, an expansible guide sleeve, and an expansible fastening bolt, all formed of sheet metal and split for expansion to fit openings in window sash, said socket and the end portion of the bolt having interfitting corrugations formed therein. 10 15

9. In a window fastenings, an expansible guide member adapted to be inserted in a window sash and having flanges thereon for securing the same in expanded condition, said member having internal means for interfitting with a fastening 20 bolt.

10. In a window fastening, an expansible guide member adapted to be inserted in a window sash and having means for securing the same in expanded condition, and a bushing of yieldable material surrounding said guide member, said member having internal means for interfitting with a fastening bolt. 25

11. In a window fastening, an expansible guide member, and a fastening bolt expansible throughout its length and slideable through said guide member and fitting said guide member in different expanded positions of the guide. 30

12. In a window fastening, an expansible guide member adapted to be inserted into a sash opening and expanded approximately to fit the same, flanges on said guide member for fastening said member in expanded position, and an expansible bolt fitting in said guide member. 35

13. In a window fastening, an expansible guide member adapted to be inserted into a sash opening and expanded approximately to fit the same, a bushing of yieldable material surrounding said member, means for fastening said member in expanding position, and an expansible bolt fitting in said guide member. 40 45

14. In a window fastening, an expansible guide member adapted to be inserted into a sash opening and expanded approximately to fit the same, a bushing of yieldable material surrounding said member, means for fastening said member in expanding position, and an expansible bolt fitting in said guide member and constructed of sheet metal and split lengthwise along a side thereof. 50
